UNITED STATES PATENT OFFICE.

PERCY W. SHAW, OF LYNN, MASSACHUSETTS, ASSIGNOR TO UNITED SHOE MACHINERY COMPANY, OF PATERSON, NEW JERSEY, A CORPORATION OF NEW JERSEY.

METHOD OF MAKING A STITCH.

1,189,394.

Patented July 4, 1916.

Specification of Letters Patent. Application filed June 20, 1914. Serial No. 846,273.

To all whom it may concern:

Be it known that I, PERCY W. SHAW, a citizen of the United States, residing at Lynn, in the county of Essex and State of Massachusetts, have invented certain new and useful Improvements in Methods of Making a Stitch; and I do hereby declare the following to be a full, clear, and exact description of the invention, such as will enable others skilled in the art to which it appertains to make and use the same.

The present invention relates to an improved method of making a stitch and more particularly to a lockstitch made with a single thread.

The object of the present invention is to provide a simple and expeditious method of forming a lockstitch with a hooked needle which may be practised either manually or with a sewing machine, and which insures the locking of each stitch securely in the work.

With this end in view one feature of the invention consists in passing two loops of thread successively through the work, passing the second loop of thread through the first, releasing the thread, and pulling upon the supply end of the thread to draw the encircling loop into the work and lock the stitch.

The invention will be clearly understood from an inspection of the accompanying drawing which illustrates somewhat diagrammatically the successive operations which are preferably performed upon the thread in practising the method of the present invention.

Referring to the drawing: Figure 1 illustrates the needle with a loop of thread engaged thereby preparatory to passing the loop of thread through the work; Fig. 2 illustrates the needle after a relative feeding movement has been imparted to the work and needle and preparatory to the engagement of the second loop; Fig. 3 illustrates the operation of passing the second loop of thread through the work and through the first loop; and Fig. 4 shows the stitch after the take-up has actuated to draw the encircling loop of thread into the work and lock the stitch and the thread cutter is operated to sever the thread between the stitch and the supply.

In the illustrated embodiment of the invention the stitch is employed in the making

of boots and shoes and is inserted through the upper 1 and the lip 2 of an insole 3. The short end of the thread is retained by a thread clamp comprising a sleeve 5 and a hooked member 6 sliding in the sleeve to clamp the thread against the end of the sleeve, as shown in Fig. 1. The thread clamp may also serve as a means for laying the bight of thread in the barb of a hooked needle 7 which is advanced through the base 60 of the insole lip and the upper into a position to engage with the loop of thread, as shown in Fig. 1. After the loop of thread has been laid in the barb of the needle, the needle is retracted while the short end of the thread is clamped to draw a loop of thread through the work. After the loop has been drawn completely through the work a relative feeding movement is imparted to the needle and the work and the needle is again advanced, the loop of thread 65 leaving the barb of the needle and sliding along the shank into a position to engage with a second loop of thread. The thread clamp is then moved back to its initial position, laying that portion of the thread between the clamp and the first loop in the barb of the needle, after which the needle is retracted, as shown clearly in Fig. 3, drawing the second loop of thread through the 70 work and through the first loop, a cast-off 75 of any suitable form serving to protect the barb of the needle and permitting the second loop to slide over the first. During the formation of the stitch the work is held in part 80 by a channel guide 8 which may project into the channel of the insole, as shown clearly 85 in the drawings.

In the illustrated embodiment of the invention a relative vertical feeding movement 95 is imparted to the work and needle, causing the needle upon its second advancing movement to pass in close proximity to or above the top of the insole lip. In drawing the second loop of thread through the work the needle is retracted sufficiently, as shown in Fig. 4, to permit the encircling loop to be pulled back into the work without disengaging the encircled loop therefrom. After the needle has been completely retracted it is actuated to release the loop and the thread clamp at the same time is actuated to release the short end of the thread. The encircling 100 loop is then drawn into the work by pulling upon the supply end of the thread, thus 105 110

binding the second loop against the work and locking the stitch, as shown clearly in Fig. 4. After the stitch has been set a thread cutting movement is imparted to the 5 knife 10 to sever the thread in close proximity to the work.

With this mode of operation a single thread lockstitch may be formed with a hooked needle which is of considerable advantage as the thread will fit closely in the hole formed in the work to hold the parts securely in place as is well known to those skilled in the art.

The operations which are performed as 15 above described and illustrated in the drawing are those which are preferred in practising the present invention. It is to be understood, however, that except as defined in the claims the invention is not limited to 20 the precise method illustrated and described.

Having explained the nature and object of the invention what is claimed is:

1. The method of making a stitch which 25 consists in passing two loops of thread successively through the work, passing the second loop of thread through the first, releasing the encircled loop, and pulling upon the supply end of the thread to draw the encircling loop into the work and lock the 30 stitch.

2. The method of making a stitch which

consists in passing two loops of thread successively through the work, passing the second loop of thread through the first, releasing the encircling loop, pulling upon the supply end of the thread to draw the encircling loop into the work and lock the stitch, and finally severing the supply thread in close proximity to the work.

3. The method of making a stitch which 40 consists in passing a loop of thread through the work, relatively feeding the needle and work, passing a second loop of thread through the work and through the first loop, releasing the encircled loop, and finally 45 drawing upon the supply end of the thread to draw the encircling loop into the work.

4. The method of making a stitch which 50 consists in clamping the short end of the thread, passing a loop of thread through the work, relatively feeding the needle and work, engaging the thread between the first loop and the short end of the thread and 55 passing a second loop of thread through the work and through the first loop, releasing the thread, and finally drawing upon the supply end of the thread to draw the encircling loop into the work.
